W. S. GUTHRIE

CARBURETOR FOR INTERNAL COMBUSTION ENGINES

Original Filed April 3, 1919

Inventor

William S. GUTHRIE.

By

John H. Attorney

UNITED STATES PATENT OFFICE.

WILLIAM S. GUTHRIE, OF LOS ANGELES, CALIFORNIA, ASSIGNOR TO MARVEL CARBURETER COMPANY, OF FLINT, MICHIGAN, A CORPORATION OF INDIANA.

CARBURETOR FOR INTERNAL-COMBUSTION ENGINES.

Original application filed April 3, 1919, Serial No. 287,277. Divided and this application filed September 8, 1924. Serial No. 736,597.

This invention relates to carburetors for internal combustion engines and is a division of my application filed April 3, 1919, Serial Number 287,277 for carburetor, the object 5 of my invention being to provide an improved construction of reservoir with a float for controlling the supply of fuel thereto.

Another object of my invention is to provide a carburetor with a fuel reservoir having a float through which loosely extends a stem so as to permit freedom of movement of the float in respect to the valve.

The invention especially consists of certain details of construction shown in the drawings and more fully described and pointed out in the claim.

The drawing shows one embodiment of the invention.

Referring to the drawing, the body 1 has 20 a main fuel reservoir 2 in which a float 3 controls the fuel valve 4 to open and close the inlet passage 5 to which the liquid is conveyed in the usual manner.

The fuel inlet valve 4—in the present case 25 a needle valve—in the embodiment shown is preferably guided at both ends so the valve will not get out of line with its seat and thereby impair the same, and it has two portions of different diameters, the smaller of 30 which passes, preferably rather loosely, through the float 3 and in the present case guiding the latter; and a cross pin 10 or the equivalent is provided on the valve somewhat below the bottom of the float. It will

thus be apparent that the float may have 35 considerable free movement to accomodate jars and vibrations and relieve the valve seat largely from shocks it would get if the float and valve were closely connected. The construction is exceedingly cheap (the use of 40 interposed levers or the like being eliminated), and it may be applied to devices other than carburetors.

The liquid flows out of the reservoir 45 through suitable passages to a main passage 29 and then to the nozzles 30 and 31.

What I claim is:—

A carburetor comprising a carbureting chamber and a fuel reservoir connected thereto, a removable cover for said reservoir 50 provided with a fuel inlet passage terminating in an enlarged passage forming a guideway, a valve seat formed at the junction of said passages, lateral branch passages extending from the enlarged passage within 55 said fuel reservoir, a valve mounted in said guideway cooperating with said valve seat and having a reduced portion, a guideway formed in the bottom of said reservoir in which said reduced portion is slidably 60 mounted, a float loosely mounted on the reduced portion of said valve and a pin extending through the reduced portion of said valve below said float.

In testimony whereof I hereunto affix my 65 signature.

WILLIAM S. GUTHRIE.
